CHICKEN ROOST, NEST, AND LITTER CARRIER

William Ische, Norwood, Minn.

Application June 9, 1938, Serial No. 212,729

9 Claims. (Cl. 119—22)

My invention relates to an improvement in chicken roost, nest and litter carrier, wherein it is desired to provide a device which is extremely sanitary and which may be kept clean with a minimum of effort.

Many various types of chicken roosts have been previously constructed and pains have been taken to mount these roosts in such a way that it is difficult for vermin of various sorts to come into contact with the roosts. Because of the fact that the roosts in order to be practical must be of some considerable length where a number of chickens are to be supported, it has been extremely difficult to keep the roosts and dropping boards clean. Furthermore, it has been difficult to clean the space beneath the dropping boards where the nests for the chickens are often located.

Difficulty has also often been experienced in keeping the chickens out of the nests at night. Instead of remaining on the roosts at night, some chickens have a tendency to remain in the nests, making them difficult to keep clean. Attempts have been made to keep the chickens out of the nests at night, but if this is done, it is necessary to open the nests again after the chickens are quiet or to open the nests early in the morning to permit hens to have some place to lay the eggs. It has further been found that after one chicken has laid an egg in a nest, another chicken will come into the nest and set on the eggs therein, keeping these eggs warm.

It is the object of the present invention to provide a roost which is supported movably on tracks mounted on the ceiling or depending therefrom so that the roost may be moved for cleaning beneath the same and so that the entire roost may be moved to a point where the chickens will be most comfortable. In the summer time the entire roosts may be moved to the center of the coop where more air for ventilating purposes is available. In cool or cold weather the roost may be moved into the position in which the chickens will be warmest. Movably mounting the entire roost in this way also eliminates all connection between the roost and the floor and the roost may therefore be maintained in a more sanitary condition.

It is a purpose of my invention to provide roosts with pivotally mounted wire guards positioned therebetween. These guards or guard trays extend above the dropping board trays and prevent the chickens from walking in the dropping board trays. When it is desired to clean the dropping board trays, the screens may be

5 pivoted out of usual position and a scraper blade may be used to clean the stationary trays.

It is a purpose of my invention to divide the dropping board into trays having sides and one end and to space these trays apart so that air may flow upwardly between the trays and over the wooden roosts positioned between and above the trays. The sides on the dropping board trays guide the scraper in cleaning the trays and the end thereupon also guides the blade from dropping over the end of the tray when the scraper is operated from the opposite end.

It is a further feature of my invention to provide a roost having a series of nests integrally connected beneath the same and to provide a tilttable screen platform in front of these nests. In entering the nests the chickens must walk over the screen platform which acts to clean dirt from their feet, thus assisting in maintaining the nests clean. This tilttable screen platform may be manually tilted at night and held in tilted position throughout the night. A latch is provided for holding the screen platform in tilted position, which latch is operated when 10 the chickens leave the roost in the morning to release the platform and permit the same to assume its normal horizontal position. Therefore, while the platform is held tilted during the night to prevent chickens from entering the nests, the platform is automatically properly positioned in the morning to enable the chickens to enter the nests.

It is a further feature of my invention to provide nests having inclined screen bottom members, the lower portion of which extends externally of the nests or of that portion of the nest upon which the chicken may rest, so that as a chicken leaves the nest, any egg therein will roll toward this lower end of the inclined bottom. Then when another hen enters the nest, the eggs will be in such a position that she cannot set upon the same while she is in the nest. This also enables the eggs to be cooled off and collected without disturbing the nesting hens.

45 It is also a feature of my invention to provide a litter carrier which is movable throughout the length of the roost to permit the droppings and dirt on the dropping board to be scraped into this carrier throughout the length of the roost.

These and other objects and novel features of my invention will be more fully and clearly set forth in the following specification and claims.

In the drawings forming a part of my specification:

Figure 1 is a perspective view of my roost, nest

and litter carrier, illustrating the general arrangement thereof.

Figure 2 is a rear perspective view of my device, illustrating the tiltable screen in tilted position in front of the nests.

Figure 3 is a cross-sectional view centrally through my roost indicated by the line 3-3 of Figure 4. The construction illustrated in Figure 3 shows a modified form of my roost support.

Figure 4 is a perspective view illustrating diagrammatically the connection between various of the roosts to operate the automatic platform release. The construction illustrated in Figure 4 shows a modified form of roost support similar to that shown in Figure 3.

Figure 5 is a cross-sectional view, similar to Figure 3, but taken centrally through one of the nests on the line 5-5 of Figure 1.

Figure 6 is a cross-sectional view on the line 6-6 of Figure 5, illustrating the manner in which the lower portion of the nests are constructed.

Figure 7 is a perspective view of the lower portion of one of the nests.

Figure 8 is a cross-sectional view through the front portion of the frame illustrating a modified form of construction.

The roost, nest and litter carrier device A comprises, in general, a roosting portion B, a series of nests C, and a litter carrying device D. All of these portions comprising the device as a whole, are movably mounted and securely connected together.

The roosting apparatus B comprises a frame 10 preferably rectangular in shape and shown comprising angle iron strips connected at the corners. A pair of upwardly extending loops 11 are secured to the frame 10 near opposite sides thereof and are connected by bolts 12 to suitable rollers 13, illustrated in Figure 5, engageable in a track 14 mounted on the ceiling or upon suitable supporting members. It may be seen that the entire frame 10 may be moved forwardly and rearwardly the entire length of the track 14.

Spaced at intervals throughout the length of the front angle member 15 and the rear angle member 16 of the frame 10, I provide upright brackets 17 and 19, respectively. The brackets 17 and 19 support the ends of roosts 20, with the exception of the center bracket 17. To each of the brackets 17 and 19, with the exception of the brackets at one extreme end of the frame, I provide saddle strips 21 designed to form a journal for wire trays 22 positioned between the brackets 17 and 19. These wire trays are preferably composed of a series of welded wire strips connected between longitudinally extending edge members 23 about which the saddle strips 21 may extend. Hook-shaped strips 24 are provided on the opposite sides of the brackets 17 and 19 to engage the opposite edge strip 23 of the trays 22. Accordingly, the wire trays 22 are pivotally supported upon the brackets 17 and 19. In Figure 1 of the drawings one of the trays 22 is shown pivoted out of usual position into the position in which the adjacent dropping board tray may be cleaned.

The dropping board trays 25 are positioned between each pair of brackets 17 and 19 and comprise a base portion 26, side walls 27, and an outwardly inclined end wall 29. The trays 25 are secured to the brackets 17 and 19 by bolts or other suitable means. When the tray 22 is pivoted out of usual position as shown in Figure

1, the dropping board tray 25 adjacent the pivoted tray may be readily cleaned by use of the usual scraper. The inclined rear wall 29 prevents the blade of the scraper from dropping over the end of the bottom of the trays and the side walls 27 guide the scraper in moving throughout the length of the tray.

Suspended beneath the front angle member 15, I provide a channel track 30 for accommodation of a roller means 31 supporting a yoke 32 having hook ends 33 to support a litter basket 34. The litter carrier 34 may be moved into position beneath any of the trays 25 by merely moving the yoke 32, the roller 31 rolling in the channel track 30. When it is desired to clean any tray, the litter carrier is moved into position beneath the same. The flexible handles 35 of the litter basket 34 enable this basket to be readily removed from the yoke 32.

The nests are constructed as best illustrated in Figures 2 and 5 of the drawings. A front wall 36 extends the length of the row of nests, and a rear wall 37 also extends the width of the nests in the front of the same. Partition walls 39 and similar end walls divide the space between the front and rear walls 36 and 37 into a series of nests. The front wall 36 is provided with a series of openings 40 therein best illustrated in Figure 2 of the drawings. The hens enter the nests through these openings 40.

The lower extremities of the partitions and end walls 39 are each provided with a cross rail 41 thereupon to support side flanges 42 of the removable nest trays 43 forming the bottom of the various nests. The nest trays 43 are preferably formed as illustrated in Figure 7 of the drawings, having a top baffle 44 which rounds the nest and holds the hen upon the upper portion of an inclined screen 45 within the trays 43. One end 46 of the trays 43 extends beyond the rear wall 37 of the nests. This end 46 is adjacent the lowermost extremity of the inclined screen bottom member 45. A cover 47 extending the length of the nests is pivoted at 48 to the rear wall 37. By opening this pivoted cover 47 the lower extremity of all of the trays 43 may be seen.

When an egg is laid upon the inclined screen 45 and the hen leaves the nest, the egg will roll slowly to the lower end 46 of the trays 43. This will place the eggs beneath the cover 47 where they may be easily removed from the nests and also will move the eggs from the portion of the nest available for use by another hen. Thus no egg will remain in the nest to be set upon by another hen and the eggs may be removed from the nests without disturbing the hens.

The nests C are supported by a pair of supporting brackets 49' at either end of the nests extending between the front and rear angle members 15 and 16. The wire screen platform 50 is pivoted between these brackets 49' at the point 51. The screen 50 in preferred form, includes a peripheral reinforcing member 52 having reinforcing rods 53 extending across the same at intervals. The screen 54 is positioned within the peripheral reinforcing member 52. When in horizontal position the platform 50 is positioned in front of the nests C so that the hens may walk across this screen platform and into the nests. When in inclined position, shown in Figure 2 of the drawings, the platform 50 closes the entrance to the nests and prevents the hens from entering the same. The platform 50 is held in horizontal position by a bracket 55 con-

nected to the central roost 20 by bolts 56 or other suitable connecting means. The platform 50 is supported in tilted position by a latch 57 which is connected to a U-shaped yoke 59 pivoted at 60 to a pair of rear brackets 19. The construction of the U-shaped yoke is perhaps best illustrated in Figures 3 and 4 of the drawings. The yoke 59 is movable between the position illustrated in full lines in Figure 3 of the drawings, and the position illustrated in dotted lines in this figure. The roost 20 is pivoted at 61 to the bracket 19 and is movable between the full line position of Figure 3 and the dotted line position shown in this figure. A latch strip 62 is pivoted at 63 to the roost 20 and is provided with a notch 64 which may engage a transversely extending pin 65 in the yoke 59.

In operation, the bracket or latch 55 firmly engages the platform 50 when the roost 20 is in the full line position illustrated in Figure 3. When the roost 20 is depressed an abnormal amount, this bracket or latch 55 disengages the platform 50 and by means of a cord 66 connected at 67 to the platform 50 and passing over a pulley 69 in the U-shaped yoke 59 and extending to the front of the roost, the platform 50 may be manually tilted into the dotted outline position. In this position the platform 50 is normally engaged by the latch 57 when the yoke 59 is in its normal full line position shown in Figure 3. When the cord 66 is engaged and pulled to tilt the platform 50, the platform 50 tilts upwardly and the yoke 59 pivots downwardly into the full line position through this manual operation, if it is not already in this downward position. This operation takes place at night when it is not desired to have the hens enter the nests during the night.

When the platform 50 is thus supported in tilted position, the roost 20 is normally in its full line position shown in Figure 3, and the yoke 59 is also in full line position. The latch 62 in this position is riding upon the pin 65 and the notch 64 is not engaging this pin as shown in the full line position of Figure 3. When several hens light upon the roost 20, the roost bar 20 pivots downwardly slightly compressing the spring 70, encircling the guide shaft 71 extending between the front angle member 15 and the top of the center bracket 17. A nut 72 on the shaft 71 permits the tension of the spring to be adjusted. Downward movement of the roost 20 moves the roost under the weight of several hens into the dotted position illustrated in the drawings. In this position, the notch 64 in the latch 62 engages the pin 65 in the yoke 59. As long as the several hens remain upon the roost 20, the yoke 59 and roost 20 remain in full line and dotted line positions, respectively. However, as soon as the hens move off from the roost 20, this roost pivots upwardly into the full line position, and the latch 62 carries the yoke 59 upwardly with the roost 20, thereby raising the latch 57 into the dotted position illustrated, releasing the platform 50. This platform 50 is suitably counter-weighted or pivoted off center to normally assume horizontal position illustrated in full lines when the latch 57 is released. The platform 50 will therefore pivot into horizontal position when the chickens leave the roost in the morning and properly position the platform so that the chickens may enter the nests C.

With this construction, it is possible for the hen to get out of the nests if she happens to be in the nest at the time the platform is tilted. It

is true that the hens are ordinarily all removed from the nests before the platform is tilted, but in some instances it is possible that a hen be in the nest by mistake at the time the platform is tilted, and in such a case it would be possible for the hen to escape. At the same time it would be virtually impossible for a hen to enter the nest when the platform is tilted, as it will be necessary for the hen to fly upwardly at a sharp angle and to rest upon the lower edge of the nest opening without flying above the level of the nest. It is virtually impossible for a hen to light upon a perch such as the bottom of the nest opening without approaching this ledge from above the level of the ledge, and therefore the tilting platform is extremely effective in preventing the hens from entering the nests.

Under some conditions it may be conceivable that the chickens might avoid the center roost 20 during the night or it might happen that an insufficient number of chickens may rest upon this central roost to depress the roost sufficiently to cause the notch 64 to engage the pin 65 and thereby release the yoke 59 to release the latch 57 from the platform 50 when the birds leave the roosts. It may therefore be desirable to provide, in addition to the above described releasing means, a means of connecting several of the roosts together so that a sufficient amount of weight on any of the roosts near the center of the device will act to cause release of the platform 50 when the birds leave the roost in the morning. To accomplish this result I provide a pair of L-shaped connecting levers 73 and 74. One end of the lever 73 is pivoted at 75 to the roost on one side of the central roost 20, while the other end is pivoted at 76 to the frame 10. Similarly, one end of the arm 74 is pivoted at 77 to a roost 20 on the opposite side of the central roost 20, and is pivoted at its other extreme end at 79 to the frame 10. These levers 73 and 74 are pivoted together at their crossing point 80 and to a vertically extending rod 81 pivoted at 82 to the central roost 20. It may be seen that weight upon the roost 20 to the right of the central roost will pivot the arm 74 about its fixed pivot 79, thereby lowering the pivot point 80 and acting to draw the central roost 20 downwardly. Similarly, when the roost 20 to the left of the central roost is moved downwardly by weight, the lever 73 will pivot about its center 76, lowering the connecting point 80 and pulling the central roost 20 downwardly. By this construction the combined weight of a number of birds on any of the roosts near the center may act to depress the central roost 20 sufficiently to cause the latch 62 to engage the yoke 59 so as to release the catch 57 when the depressing weight is released. When the parts 73 and 74 are not used, all of the roosts except that at the center are supported in a fixed position at both ends; however, when the parts 73 and 74 are used, three roosts are pivoted at one end and can move up and down at the other end.

In Figure 8 of the drawings, I disclose a modified form of track in which a channel 83 is secured directly to the front frame member 15 and the roller 31 engages in the channel 83. The depending track 30 may in this way be omitted.

The manner in which the roost is constructed has been described and the operation of the platform latching means has also been described in detail. As will be seen, the device A is movable and may be moved throughout the length of

the tracks 14 for cleaning or for culling the birds.

In accordance with the patent statutes I have described the principles of construction and operation of my roost, nest and litter carrier, and while I have endeavored to set forth the best embodiments thereof, I desire to have it understood that this is only illustrative of a means of carrying out my invention and that obvious changes may be made within the scope of the following claims without departing from the spirit of my invention.

I claim:

1. A roosting apparatus comprising a frame, a series of pairs of spaced brackets projecting upwardly therefrom, the brackets of each pair being arranged in opposed relation on opposite sides of said frame, a roost connecting the brackets of each pair, being supported thereby substantially spaced above said frame, individual dropping board pans between each pair of brackets and the next adjacent pair on said frame, and an individual wire tray positioned above each dropping board pan, each said tray comprising a substantially flat wire base and outwardly and upwardly inclined sides, each said tray having open ends, each said tray having its upper edges of said inclined walls entirely within the space between said roosts, means pivotally securing one side of each of said trays to the adjacent bracket, and means supporting the other side of each of said trays by the next adjacent bracket, to swingably support said trays above said dropping board pans.

2. A nesting apparatus comprising a frame, a series of nests supported by said frame, a tiltable platform having an edge thereof closely adjacent said nests in horizontal position of said platform, mounted on a pivot parallel to the front of the nests, and means locking said platform in horizontal position and in tilted position, said pivot supported by said frame and being spaced forwardly substantially from said nests to permit the edge of the platform adjacent the nests in horizontal position of said platform to pivot away from said nests into tilted position to provide a substantial gap between said nests and said tilted platform, or toward said nests to swing said platform into substantially horizontal position.

3. A nesting apparatus comprising a frame, a series of nests on said frame, a substantially rectangular wire netting platform supported in front of said nests, means pivotally supporting said platform along an axis parallel to, and spaced substantially from, the front of said nests, said frame being pivotal away from said nests into tilted position to provide a substantial gap between said platform and said nests, and toward said nests into substantially horizontal position, and means holding said platform in horizontal position, and in tilted position.

4. A roosting apparatus comprising, a dropping board means, a series of pairs of spaced brackets projecting upwardly from said roosting apparatus, a series of wire trays pivotally secured to said brackets and positioned over said dropping

board means, a series of roosts extending across said dropping board means at substantially right angles to an edge of said dropping board means, a track secured along said one edge of said dropping board means, and a receptacle supported by and movable along said track to receive droppings from said dropping board means.

5. A roosting apparatus comprising a frame, a series of pairs of spaced brackets projecting upwardly from said frame, a series of roosts connecting the pairs of said brackets, dropping board means extending across said frame, a series of wire trays pivotally secured to said brackets and positioned above said dropping board means, a track mounted along one edge of said dropping board means, and receptacle means supported by and movable along said track to receive droppings from said dropping board means.

6. A roosting apparatus comprising a frame, hangers supporting said frame, said hangers having roller means, track means slidably supporting said roller means, a series of dropping board trays extending across said frame, a series of roosts above the level of said trays, and an individual wire tray positioned above each said dropping board trays, a track secured to said frame extending along one end of said dropping board trays, and a receptacle supported by and movable along said track to receive droppings from said trays.

7. A roosting apparatus comprising a frame, a movably mounted roost upon said frame movable between two extreme positions, a series of nests supported by said frame, a substantially rectangular wire netting platform supported in front of said nests, means pivotally supporting said platform along an axis parallel to, and spaced substantially from, the front of said nests, a latch holding said platform in tilted position, and means connecting said latch to said roost to release said latch by movement of said roost to one extreme position, and means for holding said platform in horizontal position.

8. A roosting apparatus comprising a frame, movable roost means mounted upon said frame movable between two extreme positions, nest means supported beneath said frame, a tiltable platform having an edge thereof closely adjacent said nests in horizontal position of said platform, latch means supporting said tiltable platform in tilted position, and means connecting said roost means to said latch so that movement of said roost into substantially one extreme position may release said latch, and means for holding said platform in horizontal position.

9. A roosting device comprising a series of roosts, said roosts being pivotally connected to said roosting device, a series of nests below said roosts, a rectangular-shaped wire platform pivotally mounted in front of said nests, the rear of said platform swinging upwardly and away from said nests in tilted position to space said platform substantially from said nests in tilted position, and means for holding said platform in horizontal position, or in tilted position.

WILLIAM ISCHE.
